Des. 237,860
Patented Dec. 2, 1975

237,860

DISPENSING CONTAINER

Robert Shrier, 205 Northwest Terrace,
Silver Spring, Md. 20901

Filed Sept. 21, 1973, Ser. No. 399,494

Term of patent 14 years

Int. Cl. D9—01

U.S. Cl. D9—23

Fig. 1

Fig. 2

Fig. 3

Fig. 4

Fig. 5

Fig. 6

FIG. 1 is a side elevational view of a dispensing container showing my new design;

FIG. 2 is a front elevational view;

FIG. 3 is a front elevational view with the cap removed;

FIG. 4 is an enlarged top plan view with the cap in place;

FIG. 5 is an enlarged top plan view with the cap removed, the bottom being plain and unornamented; and

FIG. 6 is an enlarged bottom plan view with the cap removed, of a modified form of my new design wherein the only change is the recessed bottom shown.

I claim:

The ornamental design for a dispensing container, as shown and described.
